UNITED STATES PATENT OFFICE.

JOHN E. KALGREN, OF MINNEAPOLIS, MINNESOTA, ASSIGNOR TO J. R. CLARK COMPANY, OF MINNEAPOLIS, MINNESOTA, A CORPORATION OF MINNESOTA.

IRONING TABLE.

Application filed March 24, 1924. Serial No. 701,434.

The object of this invention is to provide an ironing table comprising a board in which the supports adapted for temporary engagement with the under side of the board are so arranged that downward pressure on the end of the board will be received and sustained by these supports and thereby a very firm substantial support for the board be obtained.

A further object is to provide an ironing table in which the front leg and support will sustain a load on the rounded or smaller end of the board even though the rear legs be partially folded.

Other objects of the invention will appear from the following detailed description.

In the accompanying drawings forming part of this specification,

Figure 1 is a longitudinal sectional view through an ironing table embodying my invention;

Figure 2 is a view of the under side of the table when partially folded;

Figure 3 is a detail view showing the manner of contacting the folding supports with the under side of the board;

Figures 4 and 5 are detail views of the toggle brace connection between the rear legs and the front leg.

In the drawing, 2 represents the ironing board having the usual smaller rounded end 3. At the opposite end, rear legs 4 are hinged to the under side of the board and provided with cross-bars 5 and 6 for holding the legs in their proper relation. A centrally arranged front leg 7 is hinged at 8 to the under side of the board, preferably midway between the rear legs and this leg extends at an incline when the board is set

up to a point beneath the opposite end and is adapted to rest upon the floor. Supports 9 are pivotally connected at 10 to the lower end of the leg 7 and these supports 9 preferably diverge from their lower toward their upper ends and are adapted at their upper ends to fit into cavities 11 in the under side of the board; the supports being held against separation by a cross-bar 12. This bar may be made of suitable material, metal if preferred, and is adapted to enter recesses 13 provided between the ends of brackets 14 and the under side of the board when the ends of the supports 9 enter the recesses 11. The brackets 14 have no function except as

a means for holding the supports 9 in place when the board is lifted by grasping the top. The load on the board is applied directly to the upper ends of the supports 9 and transmitted through these supports to the floor; the front leg 7 preventing the supports 9 from spreading away from the rear legs.

I prefer also to provide a connection between the lower portion of the rear legs 4 and the supports 9 consisting in a V-shaped brace 15 secured at its ends to the supports 9 and having opposite parallel end portions 16 to receive the other member 17 of the brace which is pivoted on the end 16 by means of the pin 18. One end of the V-shaped brace is turned inwardly forming a lug 19 as indicated in Figure 5, and adapted to enter a notch 20 in the bar 17 for limiting the hinged movement of one member of the brace upon the other in one direction. The brace therefore in effect forms a toggle adapted to fold in one direction when the board is collapsed and be swung in the opposite direction to a point where the members of the brace will be in alignment and serve to hold the rear legs in their normal supporting position. This brace, however, has no function in aiding the support 9 to support the board. Downward pressure on the board is sustained by the supports 9 and leg 7, even though the rear legs and the brace connected therewith may be partially folded, the walls of the cavities 11 preventing the supports 9 from slipping on the under side of the top and the front leg 7 holding the lower ends of the supports 9 from sliding on the floor.

I claim as my invention:

1. An ironing board comprising a top, rear legs pivotally connected thereto near one end, one at each side thereof, a front leg pivotally connected at the same end of the top between the pivots of the rear legs, supports extending upwardly, and pivotally connected at their lower ends to the lower portion of said front legs, a brace comprising hinged sections, said brace extending from the upper portions of said supports to the lower portion of said rear legs, a bracket on the under side of the top providing an open end recess between the top and bracket, a bar connecting the upper ends of the supports and adapted to rest

in said recess when the board is in use but movable out of the recess when the top is slightly tilted thus permitting the sections of the brace to be folded and said leg and supports collapsed.

2. An ironing board comprising a top, rear legs pivotally connected thereto near one end, supports for the other end of the top, a brace comprising hinged sections, 10 said brace extending from the lower portions of said rear legs to the upper portions of said supports, a bracket on the under side of said top providing an open ended recess between the top and bracket, a bar connecting the upper ends of the supports and adapted to rest in said recess when the board is in use but movable out of the recess when 15 the top is slightly tilted on the rear leg pivots thus permitting the sections of the

brace to be folded and said legs and supports collapsed.

3. In a folding ironing table structure, a board, stop means disposed on the under side of said board, a rear and a front leg structure pivoted to said board, a support 25 pivoted to said front-leg structure, and a folding brace comprising two rigid members hingedly connected, one end of one of said rigid members being pivotally connected to the upper portion of said support and one 30 end of the other of said rigid members being pivotally connected to the lower portion of said rear leg structure, whereby said support is held against said stop means when said table structure is in an open position. 35

In witness whereof, I have hereunto set my hand this 20th day of March, 1924.

JOHN E. KALGREN.
